UNITED STATES PATENT OFFICE

CHARLES WALTER REHBACK, OF REDONDO BEACH, CALIFORNIA

METHOD OF MAKING FISHTAIL BITS

Application filed August 31, 1927. Serial No. 216,591.

This invention relates to improvements in rotary fish tail bits and to a means and method of constructing the same. The invention may be considered as an improvement over the invention disclosed in the United States Patent No. 1,547,842 issued July 28, 1925, to Winston F. Stoddy, et al.

In rotary fish tail bits it is highly desirable that the bottom cutting edges and the wings of the bit be reenforced, that is, that these bottom edges and side edges of the bit be relatively thick and formed of a hard tough metal which will withstand abrasion while drilling. In the prior patent above referred to, wings on the bit are formed of such a metal, these wings being provided by depositing a molten metal on the body of the bit as by welding, and thus building up the thick wings of the desired material. However, when the desired material is deposited on the body of the bit by welding, it has been found that it is difficult to get a thick heavy bottom cutting edge on the bit by this method. The bottom edge of the body of the bit is relatively thin, and when the welder attempts to deposit a large quantity of metal on this edge, it frequently happens that instead of depositing the metal he burns through the edge of the body of the bit. Consequently, it is very difficult for persons other than expert and experienced welders to properly construct a bit in this manner to have the desired shape and form.

This invention provides an improved means and method of constructing a rotary fish tail bit such that practically any welder, regardless of his experience or ability, can construct a rotary fish tail bit or reconstruct one with the desired shape and form and have the desired metal forming the cutting edges and wings.

Another object of the invention is to provide a section adapted to be applied to a fish tail bit body such as by welding or any other securing means which will form the bottom cutting edges and the wings of the bit in the desired manner.

With the foregoing and other objects in view which will be made manifest in the following detailed description and specifically

pointed out in the appended claim, reference is had to the accompanying drawings for an illustrative embodiment of the invention, wherein:

Figure 1 is a view in front elevation of a 55 rotary fish tail bit constructed in accordance with this invention.

Fig. 2 is a view in side elevation of the same.

Fig. 3 is a sectional view taken upon the 60 line 3—3 upon Figure 1.

Fig. 4 is a view in front elevation of the section adapted to be applied to a fish tail bit body to form the desired construction of the bit.

Fig. 5 is a view in side elevation taken in the direction of the arrow 5 upon Figure 4.

Fig. 6 is a view similar to Figure 4, illustrating a slightly modified form of construction.

Fig. 7 is a vertical section illustrating the manner in which an old fish tail bit can be reconstructed in accordance with this invention.

Referring to the accompanying drawings wherein similar reference characters designate similar parts throughout, in order to construct the improved bit, a fish tail bit body 10 which may be of any conventional construction having the threaded pin 11 and discharge ports 12, is first provided. Two sections generally indicated at 13 and 14 are then provided, these sections being formed of a relatively hard tough metal which can withstand abrasion. These sections are approximately L-shaped in form, having their outer edges formed so as to correspond to the side and bottom edges of the fish tail bit body 10. As clearly shown upon Figures

3 and 5, the outer edges of these sections are 85 materially thicker than the inner edges, the vertical outer edge being shown thicker at 15 and the bottom outer edge being shown thicker at 16. The bottom edges of the sections 13 and 14 form the bottom cutting edges of the bit and extend toward the center of the bit to a point near the central

notch 17. It is not necessary to have the sections provide the edges within the notch 17 for the reason that the wear on the edges 90

forming the notch is very slight because these edges are near the center of the hole drilled by the bit. The sections 13 and 14 are positioned upon the opposite faces of the bit body 10 near the lower right hand corners of these faces. They are rigidly and permanently secured in place in any suitable manner, preferably by welding such as is indicated at 18. In welding the sections 10 to the body of the bit it is desirable to work as much metal between the back of the section and the face of the bit as possible, so that the body of the bit together with the deposited metal from the welding will form 15 a good backing for the sections. The sections are also welded along their outside edges as indicated at 19, and along their bottom edges. In the modifications shown in Figures 1 to 4 inclusive, apertures 20 are 20 formed through the sections and metal may be deposited through these apertures so as to "tack" the sections 13 and 14 to the body of the bit.

From the above described construction 25 it will be appreciated that the heavy bottom cutting edges and that the heavy wings are provided by a separate section of material which is fastened securely to the body of the bit. The separate sections can be cast from 30 a hard alloy, and in that manner they will be given the proper shape to provide the desired heavy cutting between edges and wings. No particular skill is required to properly fasten the sections in place against 35 the opposite faces of the body 10, and at the same time, the bit will have the proper form such being obtained from the shape of the sections 13 and 14.

In the modification shown in Figure 6, the 40 section 21 is substantially the same in form as the sections 13 and 14, except the apertures 20 are omitted. These apertures can be employed or omitted as desired, or their number may be increased over the number 45 shown in Figures 1 and 4. By means of the sections provided for constructing the bit, an old bit which has been practically worn out can be easily and quickly reconstructed and given the proper form. The method of accomplishing this is illustrated in Figure 7, 50 wherein an old body of the bit is shown at 10' having its bottom edge indicated at 22, this edge having been worn off by the previous use of the bit. To reconstruct the bit, 55 sections 13' and a corresponding section corresponding to the section 14 are positioned on opposite faces of the body 10' and welded against the face of the bit. Metal is then deposited on the back of these sections such 60 as by welding, this metal being indicated at 23. The metal 23 serves to build out the bottom of the body 10' and to rigidly connect the bottom edge 22 to the back of the section 13'. The section 13' after having 65 been secured to the face of the bit, serves as

a support for the molten metal 23 while being deposited, and assists in moulding it into the proper form.

From the above described construction it will be appreciated that a novel means and method is provided for constructing a rotary fish tail bit which is of improved construction, in that the bottom cutting edges and the wings of the bit will have the desired shape and form, and will be formed of the desired quality of metal which will withstand abrasion.

It will be understood that various changes in the details of construction may be made without departing from the spirit or scope 80 of the invention as defined by the appended claim.

I claim:

The method of constructing a rotary fish tail bit comprising providing a fish tail bit body, forming sections of relatively hard material which are adapted to form wings and bottom cutting edges for the bit, positioning said sections against the opposite faces of the bit adjacent a bottom and side edge thereof, and depositing metal as by welding about said sections and upon the back thereof, thus securing the sections to the body of the bit and forming a strong backing for said sections.

In testimony whereof I have signed my name to this specification.

CHARLES WALTER REHBACK.
